Application July 20, 1933, Serial No. 681,306

10 Claims. (Cl. 20—4)

This invention relates to improvements in acoustical construction and has particular relation to acoustical coverings for walls, ceilings, and the like, all of which are intended to be comprehended within the generic term "walls".

The use of various types of sound-absorbing materials, including both compressible and porous materials, as acoustical wall coverings, has, of course, been known in the art for many years. Such materials have included hair felt, wool felt, mineral wool, fibrous compositions, etc., in the various forms of slabs, matts, sheets, loose materials and the like. In some cases such materials have been surfaced with a porous or perforated membrane with the object of improving appearance and securing some degree of paintability and cleanability. In such cases it has been the practice to carefully refrain from painting in a manner which would close the pores or perforations in the membrane and thereby render the same impervious to the passage of air and sound waves through the membrane into direct contact with the sound-absorbing material behind the same. This precaution has been considered essential in order to avoid destruction or material impairment of the acoustical value of the construction.

In observing this precaution, many of the advantages which may be derived from the use of a surfacing membrane have been lost. The primary function of such membranes is, of course, to conceal and enclose the unsightly and unsanitary sound-absorbing material, and to present a surface which is less susceptible to dirt accumulation, may be more readily cleaned and is of high light reflectivity. The porous or perforated membranes heretofore used, however, overcome these difficulties only in small part and without entire satisfaction.

The primary object of the present invention is to provide an arrangement in which the above and other difficulties and defects are entirely overcome, without sacrificing the acoustical quality of the construction.

With the above and other objects in view, the invention consists, in general, in the use of a compressible sound-absorbing material as a wall covering, with a flexible membrane facing which is substantially impervious to the passage of air. It has been found that membranes of various types answering this general description may be used to great advantage in various relations to the compressible sound-absorbing material, certain examples of which are hereinafter disclosed in detail. More specifically, the membrane may

be arranged to be in contact with the compressible material over substantially the entire surface thereof and may be adhesively secured thereto over the entire surface or at spaced intervals. Alternatively, the membrane may be spaced from the sound-absorbing material and it may be secured in place by nails or other securing means instead of by adhesives. Both the sound-absorbing material and the membrane may be made of various materials, and a number of examples of different materials which are suitable in both cases will be set forth hereinafter.

The invention will be more fully understood by reference to the following detailed description, taken in conjunction with the accompanying drawing forming a part hereof, in which:

Figure 1 is a fragmentary sectional view of an acoustical construction including a wall covering of compressible sound-absorbing material faced with a flexible membrane in contact therewith and adhesively secured thereto over substantially the entire surface thereof;

Fig. 2 is a similar view of a modified construction in which the membrane is in contact with the sound-absorbing material over substantially the entire surface thereof but is adhesively secured thereto at spaced intervals only;

Fig. 3 is a similar view of a modification in which the membrane is spaced from the surface of the sound-absorbing material; and

Fig. 4 is a similar view of a further modification in which the membrane is secured in place in a different manner.

Referring first to Fig. 1 of the drawing, a wall or ceiling 11 is shown as having its normally exposed surface covered with a layer of compressible sound-absorbing material 12 which, in turn, is faced with a flexible membrane 13. The sound-absorbing material 12 is shown as being held in place by nails 14, although any other desired type of securing means may be utilized. The membrane 13 is secured to the face of the sound-absorbing material 12 by any suitable adhesive 15, extending in a thin layer over substantially the entire surface of the sound-absorbing material.

The sound-absorbing material 12 may consist of any one of numerous materials possessing the essential characteristic of compressibility. Sheets or slabs of wool felt are entirely suitable for this purpose. Other suitable materials are hair felt, mineral wool, compressible slabs or matts of fibrous composition, sponge rubber mats having connected pores open at the surface, and the like.

The membrane 13 may suitably consist of pa-

per of various types and qualities. Either coated or uncoated paper may be utilized and paper which has been subjected to any desired type of treatment is likewise suitable. Other suitable examples are wall paper, oil cloth, metal foil, coated fabrics, and asbestos paper which has been painted to render the same substantially impervious to air and water vapor, etc.

It has been found that the membrane does not have to be of any certain composition or possess any particular inherent characteristics such, for example, as would be possessed by a rubber sheeting. The only requirement is that the membrane be of such thickness according to the material used, and that it be so mounted as to be readily flexible, so that sound waves impinging thereon will not be largely reflected. It will be understood, of course, that materials of different composition or physical characteristics will require different limits in thickness to be suitable as surfacing membranes. For example, an aluminium foil of .0005" thickness is found to be very satisfactory, a zinc foil .01" has been found not to be satisfactory for absorption of sound at certain frequencies, while a chip paper of even .04" thickness is sufficiently flexible or vibratory to be a practical membrane. It has been found that the flexibility of the membrane is apparently the property which determines its suitability. There are definite limits of thickness for each material beyond which the flexibility is not sufficient to give good results.

From tests which have been conducted with various membranes and various compressible absorbents, it is apparent that membranes of the same degree of flexibility do not necessarily give the best results with all types of absorbents. The degree of resiliency or compressibility of the absorbent, which governs the sound-damping qualities thereof, also governs the desirable limits of flexibility of the membrane. It appears that the greater the damping qualities of the absorbent, the thicker or stiffer the membrane may be. It will be understood, however, that such variations determine the effectiveness of the invention only as a matter of degree and that suitable limits may be readily determined for each combination of materials which it may be desired to utilize. In general, the broad combination of a compressible sound-absorbing material and a flexible surfacing membrane substantially impervious to the passage of air will achieve the objects of the invention to a marked degree.

It will be seen that membranes of various materials possessing the desired characteristics of cleanability, paintability and light reflection may be readily selected. When the membrane is painted or to be painted, the flexibility must be considered and the membrane made sufficiently flexible to start with, so that the addition of successive coats of paint will not unduly decrease such flexibility. It has been found, however, that it is not necessary to use a paint of the so-called flexible type.

Fig. 2 of the drawing illustrates an arrangement similar to that shown in Fig. 1, except that the membrane 13 is secured to the face of the sound-absorbing material 12 by smaller areas of glue or other adhesive 15. This material may be applied in spots or strips only, rather than over the entire surface. The distance by which these spots or strips are separated may be varied within any desired limits so long as the membrane is supported at sufficiently close intervals to prevent sagging thereof. This leaves the membrane

free from the sound-absorbing material over a large part of its area, and, in general, permits the use of a somewhat less flexible membrane than in the first instance, where the continuous layer of adhesive increases the effective stiffness of the membrane to some extent. The use of a flexible glue or other adhesive is not necessary with either type of construction.

The arrangement shown in Fig. 3 differs from the preceding forms in that the membrane 13 is spaced outwardly from the surface of the sound-absorbing material 12. This relationship may be suitably obtained by securing the sound-absorbing material in place by means of furring strips 16 through which nails 17 extend into the ceiling or other wall. The furring strips may be uniformly spaced from the wall surface by spacing blocks 18 or other suitable means if desired. The membrane is shown in this modification as being glued or otherwise adhesively secured to the outer faces of the furring strips 16, as indicated at 19.

An alternative method of securing the membrane to the furring strips 16 is illustrated in Fig. 4, and consists in the use of outside furring strips 20 overlying the strips 16 and secured in place by nails 21 extending into the latter. Either the strips 16 or the strips 20, or both, may extend both longitudinally and transversely over any given area if desired. The membrane 13 may be initially secured in place by glue or adhesive 19 on the surface of the strips 16, although in general this additional method of attachment is not required where the outside furring strips 20 are utilized.

Any other desired means may be utilized for securing the membrane in its desired position. For example, mechanical means extending through the membrane and the sound-absorbing material into the wall or ceiling will serve to produce the desired ultimate arrangement. In any case, however, rigid attaching means should not be provided at such close intervals that the membrane will be rendered unduly stiff, and, therefore, too reflective of sound. If comparatively close nailing or the like is desirable, a more flexible membrane should be selected in order to avoid excessive reduction in its flexibility.

The high sound-absorbing efficiency which has been found to be obtained with the above-described arrangements and various other modifications, is believed to be due to the additive effect of three agencies. When sound waves impinge upon the membrane, the latter is vibrated and transmits sound to the absorbing material behind the same, which dissipates it in the same manner as such absorbents do ordinarily. It should be understood, however, that this transmission of sound by the membrane is not by actual passage of sound waves through the membrane, as would be the case if it were porous or perforated, but by vibratory movement set up in the membrane itself by the sound waves, in which there is little energy returned by reflection from the membrane. A large part of the energy is transformed into new but similar waves which are set up behind the membrane and which are directly absorbed by the sound-absorbing material. This absorption is ordinarily explained as being due to the sound waves penetrating into the interstices of the material where the energy is dissipated by conversion into heat.

The second factor contributing to the total absorption of the construction is that resulting from the compression of the combination of confined

- air and absorbing material. The absorbing material being compressible, the membrane will ride back and forth on the surface thereof, if arranged in contact therewith, as on an air cushion; in 5 cases where the membrane is spaced outwardly from the surface of the absorbing material, there is a definite air cushion and the compression of the absorbing material is transmitted therethrough from the membrane. In other words, 10 the air-felt column behind the vibrating membrane may be regarded as somewhat inelastically compressible, so that it acts as a damping means, converting a portion of the sound energy into heat energy.
- 15 The third factor contributing to the acoustical effectiveness of the combination is the consumption of energy by the work required to vibrate the membrane itself, which is also transformed into heat energy and dissipated as such.
- 20 The use of the membrane in the above described structural combination is particularly advantageous with certain types of sound-absorbent materials, such, for example, as hair felt, wool felt, etc. With such sound-absorbing materials, the combination, including the membrane, gives a 25 decidedly increased sound absorption over that of the sound-absorbent material alone. This feature, obviously, is of considerable importance.
- As above indicated, the use of a compressible 30 sound-absorbing wall covering in combination with a flexible membrane, substantially impervious to the passage of air, extending over the surface thereof, has been found to produce highly advantageous results from an acoustical stand-point, and such combination is accordingly broadly claimed herein.
- In referring to the membranes as being substantially impervious to the passage of air, it will be understood that a limitation to completely impervious and non-porous products is not intended. 40 For example, paper and similar products might not be considered to be absolutely air-tight, but, to all intents and purposes, they are substantially impervious to the passage of air, and therefore 45 fully comply with the requirements of the present invention.
- The use of substantially impervious membranes produces a further marked advantage in that 50 they prevent the material of the sound-absorbent base from sifting or dusting through the membrane covering onto the objects in the room. This objectionable result is obtained to a great extent when perforated membranes or the like are used, particularly when the building structure is subject 55 to vibrations of any kind. Painted membranes are highly advantageous because they are substantially impervious to water vapor as well as to air, and therefore dimensional changes due to changes in humidity are greatly decreased, with 60 a corresponding decrease in the tendency of the membranes to sag.
- Other terms used in the foregoing description and appended claims will be readily understood from the context. The term "wall", as above 65 indicated, is used generically to designate both walls and ceilings as well as any other partition or surface bounding a room or other enclosure. Reference to the "face" of such a wall or of a covering therefor designates the surface thereof 70 which faces inwardly toward the room, as distinguished from the rear surface. The term "covering" does not necessarily imply the extension of the covering layer over the entire surface of a wall, but may refer to only a portion of such 75 wall surface.

While only certain specific embodiments of the invention have been shown and described in detail herein, it will be readily understood by those skilled in the art that various changes and modifications in the details of construction and arrangement of parts may be made without departing from the spirit and scope of the invention, as set forth in the appended claims.

What is claimed as new and is desired to secure by Letters Patent, therefore, is:

1. An acoustical construction comprising a wall having a normally exposed surface a covering for said surface of compressible, sound-absorbent material, and a flexible membrane substantially impervious to the passage of air extending over the face of said covering and in contact therewith over substantially the entire surface thereof. 15
2. An acoustical construction comprising a wall having a normally exposed surface, a covering for said surface of compressible, sound-absorbent material, and a flexible membrane substantially impervious to the passage of air extending over the face of said covering and adhesively secured thereto over substantially the entire surface thereof. 20
3. An acoustical construction comprising a wall having a normally exposed surface, a covering for said surface of compressible, sound-absorbent material, and a flexible membrane substantially impervious to the passage of air extending over the face of said covering and adhesively secured thereto at spaced intervals. 25
4. An acoustical construction comprising a wall having a normally exposed surface, a covering for said surface of compressible, sound-absorbent material, and a flexible membrane substantially impervious to the passage of air extending over the face of said covering and in contact therewith over substantially the entire surface thereof and adhesively secured thereto at spaced intervals. 35
5. An acoustical construction for controlling the reverberation within an enclosed space which comprises surfaces bounding said space, some, at least, of said surfaces being lined with compressible coherent porous sound-absorbent material, and a thin flexible membrane substantially impervious to the passage of air covering said material, being in contact therewith and adhering thereto. 40
6. An acoustical construction for controlling the reverberation within an enclosed space which comprises surfaces bounding said space, some, at least, of said surfaces being lined with compressible coherent porous sound-absorbent material, and a thin flexible membrane substantially impervious to the passage of air covering said material, being in contact therewith and adhering thereto at spaced intervals. 45
7. An acoustical construction comprising a wall having a normally exposed surface, a covering for said surface of compressible, sound-absorbent material located in contact with said surface, and a flexible membrane substantially impervious to the passage of air extending over the face of said covering and in contact therewith over substantially the entire surface thereof. 50
8. An acoustical construction comprising a wall having a normally exposed surface, a covering for said surface of compressible, sound-absorbent material, and an impervious paper membrane extending over the face of said covering and in contact therewith over substantially the entire surface thereof. 55
9. An acoustical construction comprising a wall having a normally exposed surface, a covering for said surface of compressible, sound-absorbent material, and an impervious paper membrane extending over the face of said covering and in contact therewith over substantially the entire surface thereof. 60
10. An acoustical construction comprising a wall having a normally exposed surface, a covering for said surface of compressible, sound-absorbent material, and an impervious paper membrane extending over the face of said covering and in contact therewith over substantially the entire surface thereof. 65
11. An acoustical construction comprising a wall having a normally exposed surface, a covering for said surface of compressible, sound-absorbent material, and an impervious paper membrane extending over the face of said covering and in contact therewith over substantially the entire surface thereof. 70
12. An acoustical construction comprising a wall having a normally exposed surface, a covering for said surface of compressible, sound-absorbent material, and an impervious paper membrane extending over the face of said covering and in contact therewith over substantially the entire surface thereof. 75

9. An acoustical construction comprising a wall having a normally exposed surface, a covering for said surface of compressible, sound-absorbent material, and an impervious metal foil membrane 5 extending over the face of said covering and in contact therewith over substantially the entire surface thereof.

10. An acoustical construction comprising a wall having a normally exposed surface, a cover-

ing for said surface of compressible, sound-absorbent material, and a coated fabric substantially impervious to the passage of air extending over the face of said covering and in contact therewith over substantially the entire surface 5 thereof.
